UNITED STATES PATENT OFFICE.

WALTER WILLIAM PHILLIPS, OF LONDON, ENGLAND, ASSIGNOR TO PHILLIPS' PATENTS LIMITED, OF LONDON, ENGLAND.

DESIGN FOR AN INDIA-RUBBER SOLE-PAD FOR BOOTS AND SHOES.

48,040.

Specification for Design.

Patented Oct. 26, 1915.

Application filed April 13, 1915. Serial No. 21,139. Term of patent 14 years.

To all whom it may concern:

Be it known that I, WALTER WILLIAM PHILLIPS, a subject of the King of Great Britain and Ireland, residing at London, England, have invented a new, original, and ornamental Design for India-Rubber Sole-Pads for Boots and Shoes, of which the following is a specification, reference being had to the accompanying drawings forming part thereof.

Figure 1 is a side elevation and Fig. 2 an inverted plan view of an india rubber sole pad for boots and shoes.

I claim

The ornamental design for an india rubber sole pad for boots and shoes, as shown.

WALTER WILLIAM PHILLIPS.
